UNITED STATES PATENT OFFICE.

JULIAN THOMAS WREN, OF STEEDMAN, MISSOURI.

GATE-LATCH.

1,053,765.

Specification of Letters Patent.

Patented Feb. 18, 1913.

Application filed September 24, 1912. Serial No. 722,090.

To all whom it may concern:

Be it known that I, JULIAN T. WREN, a citizen of the United States, residing at Steedman, in the county of Callaway and 5 State of Missouri, have invented new and useful Improvements in Gate-Latches, of which the following is a specification.

The invention relates to a gate latch and more particularly to the class of self-locking 10 gate latches.

The primary object of the invention is the provision of a gate latch wherein on the swinging of a gate to closed position the latch will automatically lock the said gate in 15 such closed position and will not permit the opening thereof unless the latch is brought to released position.

Another object of the invention is the provision of a latch of this character which can 20 be conveniently mounted upon a gate post and the keeper upon the gate so as to co-operate with each other for sustaining the gate closed when swung to such position, the latch being readily released from the keeper 25 when it is desired to open the gate.

A further object of the invention is the provision of a latch of this character which is simple in construction thoroughly reliable and efficient in its purpose and inexpensive 30 in manufacture.

With these and other objects in view the invention consists in the construction, combination and arrangement of parts as will be hereinafter more fully described, illustrated in the accompanying drawings and 35 pointed out in the claims hereunto appended.

In the drawings:—Figure 1 is a fragmentary perspective view of a latch and a gate post showing the latch constructed in 40 accordance with the invention together with its keeper mounted thereon. Fig. 2 is a perspective view of the keeper removed from the gate. Fig. 3 is a perspective view of the latch.

45 Similar reference characters indicate corresponding parts throughout the several views in the drawings.

Referring to the drawings by numerals 5 designates a gate which may be of any ordinary well-known construction and in this 50 instance is of the swinging type while 6 indicates a latch post the same being also of the ordinary well known construction and is anchored in the ground in the usual 55 manner.

The latch comprises a bracket having parts 7 and 8 respectively which are preferably constructed from metal in the form of strap irons, the part 8 being disposed at right-angles to the other part and is formed 60 with a double end providing a bearing loop 9 through which is passed a latch lever 10 the latter being supported upon a pivot 11 which is passed transversely through the loop 9 and the said lever whereby the latter 65 may be rocked on the pivot for a purpose presently described. The pivot 11 is also passed through the end contiguous thereto of the part 7 thus connecting the same together, these parts being fastened in any desirable manner to the post in the position shown in Fig. 1 of the drawing.

Formed on one end of the lever 10 is a spear or arrow shaped head 12 which will be termed hereinafter a locking head and 75 is adapted to engage in a keeper presently described, the keeper comprising a resilient metal strip bent to form a substantially Y-shaped intermediate portion 13 and opposed resilient arms 14 the same being formed 80 with outwardly diverging hook shaped ends 15 with flared lips 16 and between these hook ends is adapted to engage the locking head 12 the latter being passed between the arms 14 on the closing of the gate.

85 Formed in the intermediate portion 13 and at the point of juncture of the arms 14 therewith are eyes 17 through which are passed suitable fasteners 18 the same being engaged in the gate for securely mounting 90 the keeper thereon in the position shown in Fig. 1 of the drawings.

When the gate is closed and the head 12 of the lever 10 is engaged in the hook ends 15 of the keeper and it is desired to swing 95 the gate to open position it will only be necessary to press downwardly on the free end of the lever 10 whereupon the head 12 will rise and in this manner disengage from between the hook ends 15 of the keeper 100 and thereby permit the said gate to be swung to open position.

Passed through the loop 9 and fixed therein is a stop pin 19 the latter engaging in a notch 20 formed in the lever 10, the pin 105 19 being designed to limit the lowering movement of the headed end of the said lever and thereby sustaining it in position for positive locking engagement with the hook ends 15 of the keeper.

From the foregoing it is thought that the construction and operation of the invention will be clearly understood and therefore a more extended explanation has been omitted.

5 The pivot 11 is passed transversely through the loop 9 and is in the form of a body carrying the ordinary nut so that the same can be readily detached and thereby permit the reversal of the lever 10 thus 10 changing the latch into a right hand or left hand one, the lever being provided with one or more openings 11 to permit the proper adjustment thereof in the loop 9 of the bracket.

15 What is claimed is.

1. The combination with a keeper adapted to be mounted upon a gate and having resilient arms provided with hook ends, of a latch comprising a lever having a spear shaped head engageable between the hook ends of the spring arms of said keeper, and 20

a bracket adapted to be mounted on a latch post and supporting the said lever.

2. The combination with a keeper adapted to be mounted upon a gate and having resilient arms provided with hook ends, of a latch comprising a lever having a spear shaped head engageable between the hook ends of the spring arms of said keeper, a bracket adapted to be mounted on a latch 25 post and supporting the said lever, the said bracket being provided with a loop bearing, and a pivot passed through the bearing and the lever for swingingly connecting it thereto.

In testimony whereof I affix my signature in presence of two witnesses.

JULIAN THOMAS WREN.
